CATHODE-TO-SPACER ASSEMBLY

Allan B. Dickinson, Cedar Grove, N. J., assignor
to Radio Corporation of America, a corporation
of Delaware

Application April 29, 1941, Serial No. 390,889

3 Claims. (Cl. 250—27.5)

My invention relates to radio tubes, particularly to methods and means for rigidly supporting cathode sleeves in such tubes.

In conventional radio receiving tubes where the electrodes are held at their ends in mica spacers, considerable difficulty is caused by loosened cathode sleeves. Although a sleeve may appear to be tight when assembled with its spacer, it often loosens so that it can vibrate after a few hours of use.

An object of my invention is an improved cathode sleeve and spacer assembly that will not loosen during use.

The characteristic features of my invention are defined in the appended claims and the preferred embodiment thereof is described in the following specification and shown in the accompanying drawing in which—

Figure 1 is an elevational view, partly in section, of a radio tube embodying my novel cathode and spacer assembly.

Figure 2 and Figure 3 are detailed views of my novel cathode and spacer assembly during two stages of manufacture.

The tube shown in Figure 1 is of conventional construction in so far as the envelope 1, enclosing the conventional electrode assembly 2, is concerned. The cathode sleeve 3 is exteriorly coated with an electron emissive oxide layer and internally receives an insulated heater wire. Other electrodes, such as the grid 4 and anode 5, are mounted concentric with the cathode and are supported upon side rods engaging at their ends insulating spacers 6 and 7. The spacers are commercial clear mica sheets with the laminae and their lines of cleavage parallel to the surface of the sheet.

Although the cathode sleeve may be inserted at its ends in holes in the micas and so closely fitted during assembly that the sleeves cannot move, it has been found that after several hours of use the sleeves will loosen. The slightest freedom of the sleeve in its hole will permit the sleeve to vibrate and cause microphonic disturbances in the output circuit of the tube. Where the tube is subject to continual vibration, as in aircraft or motor vehicles, slight vibration of the sleeve rapidly becomes worse, the supporting holes for the sleeve apparently being reamed out by movement of the sleeve until the holes become so large cathode-to-grid shorts may result. It is probable that the mica in contact with the cathode dehydrates at cathode temperature, causing the mica to chip or powder away. Heat will puff and decrepitate the mica, and split and separate

the thin laminae, the edges of which are easily crumbled to powder.

My novel sleeve and mica assembly eliminates crumbled mica adjacent the cathode. The sleeve 3 is provided with an embossed bead 8, which preferably is annular. The bead is spaced from the end of the sleeve, so that when the sleeve is inserted in its hole, as shown in Figure 2, to bring the bead into contact with the rim of the mica holes on one side of the mica, the end of the sleeve will protrude beyond the other side of the mica. With a pair of tweezers or pliers, opposite sides 9 of the protruding end of the sleeve are pinched to collapse the sides together. The sides 10 of the sleeve, intermediate the pinched side portion 9, are by this operation forced outwardly beyond the periphery of the sleeve. The side portions 10 are fan- or wedge-shaped and taper from the bead 8 outwardly to the rim of the sleeve. As the tapered side portions 10 of the sleeve ride outwardly over the upper rim of the mica hole, the sleeve is pulled upwardly, forcing the bead 8 into crushing engagement with the lower rim of the mica hole. The mica is hence compressed between the bead and the tapered side portions 10 of the sleeve, and although the portion of the mica in contact with the sleeve may be dehydrated by heat, the sheet cannot split, nor its edges fray and crumble.

I have made many thousands of tubes with cathodes according to my invention without detecting any looseness of the sleeve after hundreds of hours of operation of the tubes at normal operating temperatures and voltages. The effectiveness of my novel cathode-spacer assembly is demonstrated by the fact that if the bead 8 is spaced from the mica sheet when the end is pinched, so that the sleeve may move lengthwise, the same tubes develop serious microphonics and cathode-to-grid short circuits.

Particularly good results have been obtained in assembling tubes, according to my invention, of the types commercially known as 6K7, 6J7, 6SK7, 12SK7, 6SJ7, 12SJ7, 6C5 and 6J5, having mica spacers .008 to .015 inch in thickness and nickel cathode sleeves .045 inch in diameter. The nickel stock of the sleeve is about .002 inch in thickness.

My improved cathode sleeve and spacer assembly is easy to manufacture and completely obviates the trouble caused by loosened sleeves.

I claim:

1. The method of assembling the electrodes of a radio tube having a cathode sleeve and an insulating sheet comprising forming a cathode

sleeve with an annular embossed bead near one end, inserting said end through a hole in said sheet, and bringing the bead into engagement with one side of the sheet at the rim of the hole so that said end protrudes beyond the other side of the sheet, and then, while said sheet and said bead are in contact, pinching together opposite sides of said protruding end of the sleeve.

2. A radio tube comprising a plurality of electrodes including a cathode sleeve, a mica sheet engaging the ends of said electrodes to hold the electrodes in insulated spaced relation, means to secure one end of said sleeve in a hole in said sheet to prevent longitudinal and transverse movement of the sleeve in the hole, said hole being only large enough to receive the sleeve, said

means comprising a bead on the sleeve spaced from one end of the sleeve and in firm engagement with one side of the sheet, opposite portions of the wall of the sleeve within the hole being flared outwardly from the bead so that said portions embed in the edges of said hole and tighten said bead against the mica sheet.

3. A radio tube comprising an insulating sheet, an indirectly heated cathode sleeve with its end passing through a hole in said sheet, a bead on said sleeve engaging one side of said sheet, opposite side portions of said sleeve in said hole being flared outwardly to wedge the sheet at the hole against said bead.
